UNITED STATES PATENT OFFICE.

MARY J. FRANCIS AND ALLISON MOFFETT, OF GALETON, PENNSYLVANIA.

METALLIC RAILROAD-TIE.

1,116,261.

Specification of Letters Patent.

Patented Nov. 3, 1914.

Application filed July 25, 1914. Serial No. 853,092.

To all whom it may concern:

Be it known that we, MARY J. FRANCIS and ALLISON MOFFETT, citizens of the United States, residing at Galeton, in the county of Potter, State of Pennsylvania, have invented a new and useful Metallic Railroad-Tie, of which the following is a specification.

The device forming the subject matter of this application is a metallic railroad tie, and one object of the present invention is to provide a tie of this sort in which there will be no danger of short circuiting through contact between the rail and the tie, or through contact between the rail, the tie, and the tie fastening means.

Another object of the invention is to provide a device of the sort above mentioned comprising a reversible rail clip, the position of which may be altered relative to the rail and the tie to permit an elevation of the rail and a shimming thereof.

Another object of the invention is to provide novel means whereby, at once, the rail holding wedges and the rail engaging clips will be prevented from moving longitudinally of the rail.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing:—Figure 1 shows in top plan, a portion of a railroad tie constructed in accordance with the present invention; Fig. 2 is a fragmental longitudinal section on the line 2—2 of Fig. 1; Fig. 3 is a cross section on the line 3—3 of Fig. 1; Fig. 4 is a side elevation in which parts are broken away, the rail appearing in section; Fig. 5 is a view similar to Fig. 4 but showing the rail clips reversed to permit an elevation of the rail and a shimming thereof; Fig. 6 is a perspective showing one of the wedges.

In carrying out the present invention there is provided a metal railroad tie of trough shape, the tie being denoted gen-

erally by the numeral 1 and comprising a bottom 2 and side walls 3. Adjacent each end of the tie, duplicate mechanisms are provided, but one of which need be described in detail.

The side walls of the tie 1 adjacent the ends of the tie are provided with openings 4, the side walls being provided with fingers 5 which overhang the openings.

Seated in the tie 1 and fitting closely between the side walls 3 is a rail chair 6, preferably in the form of a block, and fashioned from some insulating material such as wood. The rail 7 extends through the openings 4 and the flange 8 of the rail rests on the upper face of the chair 6. Noting particularly Fig. 4 and observing the point at which the reference character 9 is applied, it will be seen that the insulating chair 6 upstands above the lower edges of the openings 4. Consequently, when the rail 7 rests on the chair 6, the rail is spaced apart, vertically, from the side walls 3 of the tie and does not come into contact therewith. There is, therefore, no opportunity for short circuiting between the rails and the tie at the points indicated.

Insulating members 11 which may be sheets of rubber or other material rest against the opposite faces of the web 10 of the rail and extend laterally along the flange 8 and downwardly along the vertical outer edges of the flange. Rail clips 12, fashioned from metal, rest on the insulating members 11. Each clip 12 is equipped along its inner edge with an upstanding rib 14 and along the outer edge of the clip there is formed a depending rib 15. The rib 14 is higher than the rib 15, for a purpose which will be set forth hereinafter.

Securing devices, preferably taking the form of wedges 16 are inserted between the fingers 5 and the rail clips 12. The wedges 16 taper horizontally as shown at 17 and 100 taper vertically as indicated at 18. Consequently, when the wedges 16 are driven to a firm seat, the rail 7 not only will be prevented from moving vertically, but, as well, will be prevented from moving horizontally. By the action of the wedges 16, the depending ribs 15 are crowded down to a firm seat on top of the chair 6.

The rail clips 12 are of a sufficient length to project beyond the side walls 3 of the tie 1, as clearly shown in Fig. 3. The smaller ends of the wedges 16 also project beyond

the side walls 3. In the wedges 16 are formed openings 19 and through the openings 19 and through openings 20 formed in the projecting ends of the clips 12, keys 21 are inserted, the keys bearing against the side faces of the fingers 5 and bearing against the outer faces of the side walls 3.

The function of the keys 21 is, at once, to hold the wedges 16 in place and to prevent 10 the rail clips 12 from moving longitudinally of the rail 7.

In order to prevent the rail chair 6 from moving transversely of the rail 7 and longitudinally of the tie 1, spikes 22 may be 15 driven into the chair, the spikes coacting with the edges of the clips 12, as clearly indicated in Figs. 1 and 2.

The chair 6 not only serves as a rail insulating element but also exercises the office 20 of a cushion.

In order to prevent water from accumulating within the tie between the blocks 6, any desired number of drain openings can be formed in the bottom of the tie at any 25 suitable distance from the blocks. One of these openings has been shown at 23 in Fig. 1.

It is to be noted that the clips 12 are provided upon their inner and outer edges, respectively, with ribs 14 and 15 of different heights, the clips being reversible to permit a vertical interchanging of the positions of the ribs, thereby to allow for an elevation and a shimming of the rail.

35 Having thus described the invention, what is claimed is:—

1. In a device of the class described, a tie having openings in its side walls and provided with fingers overhanging the 40 openings; a rail located in the openings; a rail clip coöperating with the rail; a wedge fastening means coöperating with the clip and with the fingers; and spaced securing devices engaging the fastening means, the 45 clip and the tie, to prevent relative move-

ment between the fastening means and the clip, and the clip and the fastening means upon the one hand and the tie upon the other hand.

2. In a device of the class described, a tie having openings in its side walls and provided with fingers overhanging the 50 openings; a rail located in the openings; rail clips coöperating with the rail and having their ends extended beyond the side 55 walls of the tie; wedges engaging the fingers and the clips; and keys engaging the fingers, the keys passing through the wedges and entering the extended ends of the clips. 60

3. In a device of the class described, a tie having openings in its side walls and provided with fingers overhanging the 65 openings; a rail located in the opening; rail clips coöperating with the rail and having their ends extended beyond the side 70 walls of the tie; wedges engaging the fingers and the clips; and keys engaging the side walls of the tie, the keys passing through the clips and entering the wedges. 70

4. In a device of the class described, a tie having overhanging fingers; a rail located between the fingers; clips coöperating with the rail; and securing devices engaging the 75 clips and the fingers; the clips being provided upon their inner and outer edges with ribs of different heights, and the clips being reversible to permit a vertical interchanging of the positions of the ribs, thereby to allow for an elevation and a shimming of 80 the rail.

In testimony that we claim the foregoing as our own, we have hereto affixed our signatures in the presence of two witnesses:

MARY J. FRANCIS.
ALLISON MOFFETT.
